UNITED STATES PATENT OFFICE.

ARCHIBALD A. PORTER, OF GRIFFIN, GEORGIA.

IMPROVEMENT IN DESKS AND CHAIRS COMBINED.

Specification forming part of Letters Patent No. 120,455, dated October 31, 1871.

To all whom it may concern:

Be it known that I, ARCHIBALD A. PORTER, of Griffin, in the county of Spalding and State of Georgia, have invented a new and useful Improvement in School-Desk or Office-Chair; and I do hereby declare that the following is a full, clear, and exact description thereof, which will enable others skilled in the art to make and use the same, reference being had to the accompanying drawing forming part of this specification.

Figure 1 is a side view of my improved desk or chair, part being broken away to show the construction. Fig. 2 is a top view of the same, the desk-board being turned back and sectioned to show the construction.

My invention has for its object to furnish an improved school-desk or office-chair, provided with a desk or writing-board, which shall be so constructed that the said desk or writing-board may be conveniently turned back out of the way; and it consists in the construction and combination of the various parts of the desk as herein-after more fully described.

A is the chair or seat, which may be an ordinary office-chair, or a chair made expressly for the purpose. B is a ring or socket, from which project two arms, C D, parallel or nearly parallel with each other. The arm C is made shorter, and its inner end is secured to the forward end of the right-hand arm of the chair A. The other arm or rod D is made longer, and extends back along the right-hand arm of the chair, and its rear end is attached to a bracket attached to the said arm near the back of the chair. Upon the longer arm D is placed a socket or sleeve, E, upon the side of which is formed a projection, by means of which it is swiveled to the under side of the right-hand end of the desk or writing-board F, so as to hinge and swivel the said board to the said arm or rod. To the inner corner of the left-hand end of the desk or writing-board F is attached a notched pin or catch, G, which passes

through a hole in a small plate, H, attached to the forward end of the left-hand arm of the chair A, where it is secured in place by a spring-catch, I. If desired, the outer corner of the left-hand end of the board F may be supported by a brace attached to the frame of a chair; but this will only be necessary in the larger chairs. By this construction the desk or writing-board F, when not required for use, may be turned up into a vertical position, turned down, either forward or back upon its swivel, and slide back at the side of the chair out of the way. The ring or socket B is designed to receive an ink-well, J, which is sunk into said ring or socket C so as not to interfere with the desk-board F when arranged for use. The pen is inserted in the ink-well J through a conical or cup-shaped hole in the desk F, which hole is lined with a similarly-shaped metal plate, K, to receive any ink that may drop from the pen and conduct it back into the well J. L is a small trough pivoted at one end to the under side of the forward part of the desk F, to receive pens and pencils. In the under part of the chair A is placed a drawer, M, which may be drawn out at either side of the chair, and which is designed to receive slates, books, papers, &c.

Having thus described my invention, I claim as new and desire to secure by Letters Patent—

1. The arms C D, swiveled socket E, and spring-catch G H I or equivalent catch, with the chair A and desk F, substantially as herein shown and described, and for the purpose set forth.

2. The combination of the ring or socket B, so constructed as to receive an ink-well, J, with the arms C D, and perforated desk or writing-board F, substantially as herein shown and described, and for the purpose set forth.

ARCHIBALD A. PORTER.
